(57) **CLAIM**

The ornamental design for a waistband as shown and described.

DESCRIPTION

FIG. 1 is a front elevation view of a waistband in accordance with my design;

FIG. 2 is a rear elevation view thereof;

FIG. 3 is a top plan view thereof;

FIG. 4 is a bottom plan view thereof;

FIG. 5 is an enlarged first side elevation view thereof; and,

FIG. 6 is an enlarged second side elevation view thereof.

The dash-dash lines depict portions of the waistband that form no part of the claimed design. The dash-dot-dot-dash broken lines show a symbolic break in the length of the strap that forms no part of the claimed design.
